HARVEY HUBBELL, OF BRIDGEPORT, CONNECTICUT.

CANDLE PULL SOCKET.

Application filed May 9, 1923. Serial No. 637,643.

This invention relates to electric light fixtures and especially to candle sockets and the means for securing the same to a fixture bracket.

It is an object of the invention to provide an approved and simple means for securing a candle socket on a fixture arm which will facilitate connection of the leads to the binding posts and which will also facilitate assembling. It is also an object of the invention to provide an improved hickey and means for securing the same to the insulating body member of the candle socket whereby they may be easily assembled or disconnected. It is a further object of the invention to provide an improved construction and arrangement of the insulating elements upon which the switch and contacts are mounted.

With the foregoing and other objects in view, I have devised the construction illustrated in the accompanying drawing, in which

Fig. 1 is a partial side elevation and a partial sectional view of a candle socket complete mounted on the end of a bracket arm.

Fig. 2 is a longitudinal section in a plane substantially at right angles to that of Fig. 1, the upper portion of one of the body members being shown in elevation.

Fig. 3 is a partial side elevation and a partial sectional view of the body members and hickey removed from the shell.

Fig. 4 is a bottom plan view of the hickey in position on the shell.

Fig. 5 is a top plan view of the means for securing the hickey to the body members on a somewhat enlarged scale.

Fig. 6 is a side elevation of the hickey and means for securing the same to the body members, but showing the two members separated.

Fig. 7 is a similar view thereof showing the members connected together.

Fig. 8 is a view showing the elements separated as in Fig. 6 but looking from the right to Fig. 6.

Fig. 9 is a similar view showing the members connected, and

Fig. 10 is a top plan view of the insulating blocks with the screw shell lamp contact removed.

At 10 I have shown the end of a fixture arm through which the lead wires 11 pass to the socket and I have shown mounted there-

on the usual canopy 12; within this canopy is usually mounted a cup member 13 which receives the lower end of the tubular socket shell 14 enclosing the insulating body comprising members 15 and 15' carrying the lamp contacts 16 and 17 and the switch mechanism 18. The body members and the elements carried thereby are separated from the tubular shell by the usual insulating sleeve 19.

The switch may be of any desired type, but I have shown a pull switch comprising a segment 20 connected to a pull chain 21 whereby the same may be oscillated to rotate the switch contacts 22 with a step by step action through suitable ratchet mechanism in any desired manner, and as this forms no part of my present invention, I have not shown it in detail. The stationary switch

contacts are indicated at 23 and 24, the contact 23 being connected to the center lamp contact 17 by means of the support 17' on which contact 17 is mounted, and the contact 24 being connected with the binding post 25

carried by a suitable plate 26 in a recess 27 in one side of the body member 15. The support 17' is secured to and between the insulating blocks 15 and 15' adjacent the upper ends thereof by screws 17² and 17³

extending through these blocks, screw 17³ being extended inwardly a sufficient distance if desired to form a stop to limit the backward movement of the segment 20. On the opposite side of body member 15' is another

recess 28 in which is mounted the other binding post 29 carried by a plate 30 and which is connected to the screw shell lamp contact 16 through a U-shaped spacing element 16'

and a screw 16² which connects plate 30 with element 16'. There are two of these spacing elements the other being indicated at 16³. They also serve to secure the insulating blocks 15 and 15' in spaced relation, being

connected thereto by screws 16² and 16⁴

passing through the blocks. These elements 16' and 16³ also support the screw shell lamp contact 16 to which it is secured by screws 16⁵. The two recesses 27 and 28 extend at

their lower ends to the lower end of body members 15 and 15' to receive the lead wires 11 as shown in Figs. 1 and 3.

Secured to the body members 15 and 15' at the lower ends thereof is a transverse plate 31 having notches 32 on its opposite sides adapted when the plate is secured to the body members to align with the open

ends of the recesses 27 and 28 in the body members. Secured upon the upper side of this plate, by any suitable means such as rivets 33, is means for securing this plate to the body members. In the present instance it comprises a plate 34 having two sets of upwardly extending arms 35 and 36 placed substantially in the form of a rectangle as shown in Fig. 5, the arms 35 being extended into the space 37 between the body members for carrying the switch and secured therein by suitable screws 38. The arms 36 are provided with transversely extending screws 39, and the plate 34 is provided with elongated openings 40 in alignment with the outer surfaces of the arms 36 to receive upwardly extending spaced fingers 41 of the hickey. These fingers are provided with notches 42 leading from their upper ends adapted to receive the body portions of the screws 39. There is a counter-sink at the closed ends of these notches as shown at 43 and the screws 39 are provided with tapered heads to seat in these counter-sinks when the screws are tightened to the securing position. The hickey preferably comprises a collar 44 internally threaded so that it may be threaded on the end of the fixture arm 10, and it is also provided with a flange 45 adapted to be extended through an opening in the U-shaped plate 46, which includes the fingers 41. By rolling over the flange 45 as shown in Figs. 1 and 2, the plate 46 and the collar 44 are securely fastened together.

In assembling, the hickey including the collar 44 and U-shaped member 46 is threaded onto the end of the fixture arm 10, the ends of the lead wires having been brought out through this arm, the fingers 41 are inserted in the openings 40 and the screws 39 seated in the notches 42. These screws are now tightened so that the tapered portion on the under sides of their heads seat in the counter-sinks 43 and securely fasten the fingers of the hickey to the arms 36 and thus to the body member, as when the heads of the screws 39 are thus seated in the counter-sinks 43 the arms 36 and fingers 41 cannot be separated. If it is desired to separate the body member from the hickey all that is necessary is to loosen the screws 36 to remove their heads from the counter-sinks 43, when the body member may be withdrawn from the hickey. It will be noted that as the arms 36 and screws 39 are located in the space between the insulating body members 15 and 15' that they are above the top of cup 13, the height of which is fixed, and so these screws are accessible for easily connecting and disconnecting the body members with and from the hickey after the hickey is mounted in position on the fixture. Before placing the body member on the hickey in assembling, the lead wires 11 may be bent

to opposite sides thereof, then after the body member is secured in position, it will be apparent their free ends may be easily secured to the binding posts 25 and 29. As the binding posts are in open recesses in the lateral walls of the body member, it will be apparent that they are perfectly accessible. After the connections are properly made the insulating sleeve 19 and shell 14 may be slid down over the body member from the upper end thereof. The pull chain 21 extends through a guiding bushing 47 in the plate 31 and a similar guide 48 in the canopy 12 and cup 13, projecting below the same where it terminates in the usual acorn 49 by which the switch may be operated. This construction and arrangement of the insulating body members for carrying the switch mechanism, lamp contacts and binding posts, and also the means for securing the insulating body members to the fixture arm, provide a construction which is simple and strong, and one which may be much more easily assembled and connected up than those now generally in use. At the same time they allow easy removal of the candle socket with its switch mechanism for inspection and repair.

Having thus set forth the nature of my invention, what I claim is:

1. In a candle socket, an insulating body, contacts carried thereby adapted for connection to conducting wires, a transverse plate secured to the end of the body provided with upwardly extending arms, screws carried by said arms and located above the plate, a supporting hickey below the plate provided with spaced upright fingers having means to engage said screws to detachably secure the hickey to the body, and means for securing the hickey to the end of a fixture arm.

2. In a candle socket, an insulating body, contacts carried thereby adapted for connection to conducting wires, a transverse plate at the end of the body provided with two sets of upright arms, means for securing one set of these arms to the body, a supporting hickey provided with spaced upright fingers, and means for detachably securing said fingers to the other set of arms carried by said plate.

3. In a candle socket, spaced longitudinally extending insulating body members, contacts carried thereby adapted for connection to conducting wires, a supporting plate having arms secured to the body members and upwardly extending arms carrying transversely extending screws between the body members above the plate, a supporting hickey below the plate provided with spaced fingers having recesses extending from the ends thereof adapted to receive said screws to secure the hickey to the body members, and means for securing the hickey to the end of a fixture arm.

4. In a candle socket, an insulating body, contacts carried thereby adapted for connection to conducting wires, a plate secured to the lower end of the body provided with 5 upwardly extending spaced arms and openings at the bases of these arms, transversely extending screws carried by said arms, and a supporting hickey having upwardly extending spaced fingers extending through said 10 openings and provided with notches leading from the free ends thereof adapted to receive said screws and also provided with counter-sinks in said notches to receive the heads of the screws to secure the hickey to 15 the plate.

5. In a candle socket, spaced longitudinally extending insulating body members, contacts carried thereby adapted for connection to conducting wires, a plate secured to 20 the lower ends of the body members provided with upwardly extending spaced arms located between said members, a supporting hickey below the plate having upwardly extending spaced fingers at the sides of said 25 arms, and screws located above the plate and accessible for operation through the space between the body members for securing the arms and fingers together.

6. In a candle socket, longitudinally extending insulating body members, lamp contacts carried by said members at the upper ends thereof, a pull switch carried by said members having a pull chain leading therefrom, a plate secured to the lower ends of 30 the body members having a guide for said chain and upwardly extending spaced arms located between said body members, a sup- 35

porting hickey below the plate having upwardly extending spaced fingers, and means located above the plate and accessible for operation through the space between the body members for detachably connecting said fingers to said arms. 40

7. In a candle socket, longitudinally extending insulating body members provided with recesses in their outer walls leading from the lower ends thereof, contacts carried by said body members, binding posts in said recesses, means for forming electrical connection between the binding posts and contacts, a plate secured to the lower ends of the body members and having upwardly extending spaced arms between these members, a hickey below the plate having upwardly extending spaced fingers arranged intermediate 45 said recesses and also having a tubular portion for the passage of lead wires to said binding posts, and means located above the plate for detachably securing said fingers to 50 said arms.

8. In a candle socket, spaced longitudinally extending insulating body members, switch mechanism mounted between said members, lamp contacts mounted at one end of said members and in circuit with said switch mechanism, a support having upright arms secured to said members adjacent the other ends thereof and other arms between the body members, a supporting hickey having upright fingers adjacent the latter arms, and transversely extending 55 screws for securing fingers to said arms. 60

In testimony whereof I affix my signature.
HARVEY HUBBELL.
